COLLAPSIBLE CHAIR

William L. Gittings, Racine, Wis., assignor to Gold Medal
Folding Furniture Company, Racine, Wis., a corporation of Wisconsin

Filed Dec. 2, 1958, Ser. No. 53,625

Term of patent 14 years

Figure 1 is a perspective view of a collapsible chair embodying a design in accordance with the invention; and Figure 2 is an elevational side view of the arm assembly shown in Figure 1.

The dominant features of the design are shown in full lines and reside in the rearwardly inclined appearance of the arm rest assembly including the arm rest and its supporting spindle and the right angular relationship therebetween, substantially as shown.

I claim:

The ornamental design for a collapsible chair, substantially as shown and described.
